2 SHEETS—SHEET 2.

UNITED STATES PATENT OFFICE.

ALPHONSE POIRIER, OF SPOKANE, WASHINGTON, ASSIGNOR TO ALBERT J. COX, OF SPOKANE, WASHINGTON.

SIGNAL APPARATUS.

Application filed April 4, 1922. Serial No. 549,586.

To all whom it may concern:

Be it known that I, ALPHONSE POIRIER, a citizen of the United States, residing at Spokane, in the county of Spokane and 5 State of Washington, have invented certain new and useful Improvements in Signal Apparatus, of which the following is a specification.

This invention relates to signal apparatus 10 for automobiles and other motor vehicles, and designed to give notice to the traffic in front of and to the rear of the car when the driver thereof is about to make a turn, or to slow up preparatory to coming to a 15 stop; or for any other purpose.

The invention has for its object to provide a novel and improved apparatus of the kind 20 stated embodying a pair of illuminated casings bearing inscriptions, said casings being rotatable to display the desired inscription, together with a pointer which is pivoted to point in various directions according to the 25 inscriptions to be displayed. The pointer is operated simultaneously with the casings, and the positions it assumes correspond to the requirements of the generally prevalent 30 traffic regulations in regard to hand signaling.

With the object stated in view, the invention 35 consists in a combination and arrangement of parts to be hereinafter described and claimed, and in order that the same may be better understood, reference is had to the accompanying drawings, wherein—

Figure 1 is an elevation of the apparatus; Figures 2 to 4 are diagrammatic elevations showing the different kinds of signals to be displayed; Figure 5 is a cross-section on the line 5—5 of Figure 1; Figure 6 is 40 a horizontal section on the line 6—6 of Figure 1; Figure 7 is a sectional detail of a switch mechanism, and Figure 8 is a diagram showing certain electric circuits.

Referring specifically to the drawings, 10 45 denotes an elongated housing of sheet metal or other suitable material which is horizontally positioned to extend sidewise and outwardly from the body of the car. The housing is carried by a tubular supporting 50 arm 11, and it is supported in the position stated by a suitable clamping member 12 carried by the arm 11 and attached to the windshield support 13. It will be understood, of course, that any other means may be pro-

vided for supporting the housing 10 in 55 proper display position on the car.

To the inner end of the housing is fastened a hollow coupling member 14 having a center branch 15 and two other branches 15^a on opposite sides of the center branch. 60 These branches abut squarely against the outside of the inner end wall of the housing. The coupling member 14 is carried by the arm 11, it being fitted to one end of the latter. The other end of the arm 11 65 extends over into the driver's compartment of the car, and at this end is located a crank handle 16 for operating the signal members to be presently described.

The connection between the coupling 70 member 14 and the housing 10 is made by a pair of sleeves 17 having one end portion externally screw-threaded, and provided intermediate their ends with an outstanding annular flange 18. The threaded ends of the 75 sleeves 17 pass through apertures in the housing end wall and are screwed into the branches 15^a, so that the flanges 18 seat firmly against the housing end wall on the inside thereof. The housing end wall is in 80 this manner firmly clamped between the flanges 18 and the extremities of the two branches 15^a of the coupling member 14. The center branch 15 of the coupling member is located over an aperture 19 in the 85 housing end wall.

The unthreaded ends of the sleeve 17 which are located in the housing 10 serve as bearing supports for one end of a pair of rotatable and illuminated casings 20, said 90 casings being supported at their opposite ends by pivot studs 21 carried by the outer end wall of the housing.

Each casing 20 is square in cross-section, and its four sides are made transparent by 95 openings therein fitted with panes 22 of glass or other transparent material. Three of these panes contain inscriptions, and the other pane is left blank. The inscriptions may be "Right," "Left" and "Slow," and 100 they are displayed through front and rear display openings 23 in the housing 10, so that they are visible from the rear as well as from the front of the car. The bearing or pivot members 17 and 21 support the casings 105 20 for rotation about a horizontal axis, and they extend laterally from the car in the same direction as the housing 10.

The casings 20 are rotated to display the desired inscription, by means of the crank handle 16, the same being fastened to a shaft 24 passing through the arm 11, the coupling member 14, the center branch 15 of the latter, and the aperture 19 in the inner end wall of the housing 10, and extending a short distance into said housing, in which latter it is fitted with a spur gear 25 which is in mesh 10 with pinions 26 running loosely on the bearings or pivots 17 and fastened to the inner end walls of the casings 20. The sleeves forming the bearings or pivots 17 extend into the casings 20, and as they are stationary 15 they may be employed for supporting the lamps 27 by which the casings are illuminated. These lamps are incandescent electric lamps carried by ordinary slip sockets 28 which are carried by the sleeves and 20 secured thereto by clamping rings 29. The sleeves have projecting end tongues 30 on which the sockets 28 seat and to which they are secured by the clamps 29. This connection permits ready removal of the lamps 25 for dismounting the apparatus. Figure 6 shows one of the lamps removed, and in Figure 5 both lamps are shown removed.

In addition to the illuminated casings 20, the apparatus also employs an arrow-shaped 30 pointer or similar indicator member 31 which is rotatable simultaneous with the casings. This pointer is normally positioned in the housing 10 and it is rotatable to point in various directions according to the inscriptions displayed through the sight openings 23.

At the outer end of the housing 10 are outstanding ears 32 between which the inner end of the pointer 31 is positioned, and pivoted on a bolt 33 passing through said ears. 40 In the bottom of the housing 10 is a slot 34 through which the pointer swings into and out of the housing.

The pivoted end of the pointer has gear 45 teeth 35 which are in mesh with a spur gear 36 fastened to the outer end of one of the casings 20, so that the pointer may swing to and from display position when the casing is rotated. Continuations of these gear 50 teeth across the pointer are had by apertures 35^a.

When in non-display position, the pointer 31 is inside the housing 10, and occupying a horizontal position between the casings 20. 55 In this position of the pointer, the casings 20 are also in non-display position, the blank transparencies 22 showing through the front and rear openings 23 of the housing 10. Figure 1 shows the parts in this position. 60 When the casings 22 are rotated to display the "Slow" inscriptions, the pointer 31 swings downwardly out of the housing 10 through the slot 34 to point downwardly, as shown in Figure 2. When the casings are 65 rotated to display the "Left" inscriptions,

the pointer swings to assume a horizontal position, and points straight out from the outer end of the housing 10, as shown in Figure 3. When the casings are rotated to display the "Right" inscriptions, the pointer 70 swings to assume an upright position so that it now points upwardly, as shown in Figure 4. After each signal the casings 20 will be rotated to expose the blank transparencies 22 through the sight openings 23, and simultaneous with this movement of the casings, 75 the pointer swings back into the housing 10, so that the signal elements are now back to non-display position.

A switch device is also provided for controlling the lamps 27. For this purpose there is rigidly mounted on the arm 11, adjacent to the hub of the crank handle 16, a cap 37 of insulating material in the outer end of which are embedded two spaced contact points 38. On the shaft 24 is mounted a disk 39 of insulating material in one side of which is embedded an arcuate conductor strip 40. The disk 39 is fast on the shaft 24 to turn therewith, and for this purpose, 80 the shaft may be squared as shown in Fig. 7, and the disk provided with a correspondingly shaped center aperture to receive the shaft. The disk 39 is located between the cap 37 and the hub of the crank handle 16, 85 and its side in which the conductor strip is embedded is contiguous to the end of the cap 37 in which the contact points 38 are embedded, so that said strip may engage the contact points and bridge the same. This 90 action takes place when the shaft 24 is rotated to place the signal devices in any one of the hereinbefore described display positions, and as the circuit of the lamps 27 is now closed, the casings 20 are illuminated 95 so that the inscriptions may be clearly visible at night-time. The pointer 31 is illuminated through the slot 34. When the shaft 24 is turned to bring the signal devices back to non-display position, the conductor strip 100 40 rides off one of the contact points 38, thereby breaking the circuit of the lamps 27.

The lamp wires 41 enter the arm 11 through an aperture 42 therein, and one of the wires is connected to one of the contact 115 points 38, the other wire leading to one side of a battery and the other current source 43 having its other side wired to the other contact point 38. Figure 8 illustrates this wiring diagrammatically. The lamp wires 120 in going to the lamps 27 pass through the member 14, the branches 15^a, and the tubular members 17.

I claim—

1. A vehicle signal apparatus comprising 125 a housing having a display opening, a rotatable illuminated casing in the housing having transparent sides bearing inscriptions visible through the display opening of the housing, a pointer in the housing sup- 130

ported for a swinging movement to project from the housing in different predetermined positions, means for rotating the casing to selectively display the inscriptions, and 5 means for effecting the operation of the pointer simultaneously with the rotation of the casing.

2. A vehicle signal apparatus comprising 10 a housing having a display opening, a rotatable illuminated casing in the housing having transparent sides bearing inscriptions, and a blank side, said sides being visible through the display opening of the housing, and the blank side being normally in 15 display position, a pointer in the housing supported for a swinging movement to project from the housing in different predetermined positions, means for rotating the casing to selectively display the sides thereof through the display opening of the housing, and means for effecting the operation 20 of the pointer simultaneously with the rotation of the casing, said pointer swinging into the housing when the casing is rotated 25 to display the blank side, and out of the housing when the casing is rotated to display the inscribed sides.

3. A vehicle signal apparatus comprising 30 a housing having display openings on opposite sides, a rotatable illuminated casing in the housing back of each display opening, and having transparent sides bearing inscriptions which are visible through said opening, a pointer in the housing between 35 the casings and supported for a swinging movement to project from the housing in different predetermined positions, means for simultaneously rotating both casings to selectively display the inscriptions thereof, 40 and means for effecting the operation of the pointer simultaneously with the rotation of the casings.

4. A vehicle signal apparatus comprising 45 a housing having a display opening, a rotatable illuminated casing in the housing having transparent sides bearing inscriptions visible through the display opening of the housing, a pointer in the housing supported for a swinging movement to project 50 from the housing in different predetermined positions, means for rotating the casing to selectively display the inscriptions, and

means for effecting the operation of the pointer simultaneously with the rotation of the casing, said pointer swinging out of the 55 housing when the inscriptions are displayed, and into the housing when the casing is rotated to place the inscriptions in non-display position.

5. A vehicle signal apparatus comprising 60 a housing having display openings on opposite sides, a rotatable illuminated casing in the housing back of each display opening, and having transparent sides bearing inscriptions which are visible through said 65 opening, a pointer in the housing between the casings and supported for a swinging movement to project from the housing in different predetermined positions, means for simultaneously rotating both casings to selectively display the inscriptions thereof, 70 and means for effecting the operation of the pointer simultaneously with the rotation of the casings, said pointer swinging out of the housing when the inscriptions are displayed, and into the housing when the casings are rotated to place the inscriptions in 75 non-display position.

6. A vehicle signal apparatus comprising 80 a housing having a display opening, a rotatable illuminated casing in the housing having transparent sides bearing inscriptions visible through the aforesaid display opening, a pointer in the housing pivotally supported for a swinging movement to project 85 from the housing in different predetermined positions, a gearing between the casing and the pointer, and means for rotating the casing.

7. A vehicle signal apparatus comprising 90 a housing having a display opening, a rotatable illuminated casing in the housing having transparent sides bearing inscriptions visible through the aforesaid display opening, a pointer in the housing pivotally 95 supported for a swinging movement to project from the housing in different predetermined positions, a gear on the pivoted end of the pointer, a gear carried by the casing and in mesh with the pointer gear, and 100 means for rotating the casing.

In testimony whereof I affix my signature.

ALPHONSE POIRIER.
